US00D888462S

(12) United States Design Patent (10) Patent No.: US D888,462 S
(45) Date of Patent: * Jun. 30, 2020

(54) PILLOW WITH SUPPORTS

(71) Applicant: CosMedPillow LLC, White Plains, NY (US)

(72) Inventors: Carolyn Gang, White Plains, NY (US); Marion Garfield, New York, NY (US)

(73) Assignee: COSMEDPILLOW LLC, White Plains, NY (US)

() Term: 15 Years

(21) Appl. No.: 29/614,511

(22) Filed: Aug. 21, 2017

(51) LOC (12) Cl. 06-09

(52) U.S. Cl.

USPC D6/601

(58) Field of Classification Search

USPC D6/333, 334, 335, 377, 381, 382, 393, D6/596, 601, 604, 716.5; D12/316; D15/8; D21/503, 803, 808, 809; D23/284, 304; D24/184, 191; D30/118

CPC A47G 9/0253; A47G 9/10; A47C 7/383; A61F 9/04
